UNITED STATES PATENT OFFICE.

GEORGE LIPSCHUTZ, OF PHILADELPHIA, PENNSYLVANIA.

ELECTRIC ATTACHMENT PLUG.

Application filed May 28, 1927. Serial No. 195,092.

This invention relates to electrical connectors and more particularly to an electric attachment plug for use in connection with electric sockets, particularly of the wall 5 type.

Among the objects of this invention is the provision of an attachment plug of the pin type having means for facilitating the ready removal or withdrawal of the plug from its 10 socket without imposing any strain upon the electric cord.

Another object of the invention is the provision of a plug, the body of which is provided with a central opening or aperture 15 through which one's finger may be inserted to facilitate the withdrawal of the plug, thus avoiding the usual tendency to remove the plug by pulling on the conductor cord and so causing premature wear and tear thereof.

Still another object of the invention is the provision of an attachment plug comprising a pair of complementally formed main body members between which a pair of separable connector blades are arranged to be clamped 20 securely in position.

Still another object is to eliminate the necessity for employing screws or similar securing elements for attaching the ends of the electric cord to the connector blades, the connections between the conducting wires and the plug blades being simply and readily effected merely by clamping the body members of the plug and the intermediately disposed blades securely together.

Still another object of the invention is the provision of an attachment plug which is easy to assemble, efficient and durable in use, and simple and inexpensive to manufacture.

Further objects, and objects relating to details and economies of construction will appear more fully hereinafter, the invention consisting substantially in the construction, combination, and relative arrangement of parts, as described in the following specification, illustrated in the drawings showing a preferred form of the invention, and finally pointed out in the appended claims.

In the drawings:

Figure 1 is a side elevation of the attachment plug embodying the principles of this invention;

Figure 2 is an inside face view of one of the body members showing the relative arrangement of the connector blades and the 55 manner of securing the wires thereto;

Figure 3 is a vertical longitudinal section taken on the line 3-3 of Figure 1;

Figure 4 is a transverse section taken on the line 4-4 of Figure 1; and

Figure 5 is a view similar to Figure 3, but 60 showing a modified form of the invention.

Referring to Figures 1 to 4 of the drawing, it will be seen that the attachment plug 10 comprises a pair of complementally formed body members 11 and 12 preferably 65 composed of insulating or non-conducting material. These body members are each provided with an enlarged central aperture or opening 13 and on either side of this opening the inner face of each member is provided 70 with a groove 14, the ends 15 of which terminate short of the attaching face 16 of the plug while the opposite ends 17 thereof merge together to provide an enlarged groove 18.

The inner faces of the members 11 and 12 are each further provided with a pair of connector blade receiving and retaining grooves 19, these latter grooves being of substantially right-angle form having branches 20 80 intersecting the grooves 14 and branches 21 extending outwardly to the attaching face 16 of the plug.

The members 11 and 12 formed as just described are exact counterparts of one another 85 and are arranged to be clamped together by means of the bolts 22 and 23 which project through suitable openings provided for the purpose. Connector blades or prongs 24, each of substantially L-shape, are arranged 90 to be removably clamped between the members 11 and 12 with the inner ends thereof seated within the grooves 20-21. Due to the angular form of these grooves the connector blades 24 are retained securely in position against either lateral or longitudinal displacement with respect to the plug. At the end of the plug opposite the connector blades 24 the enlarged grooves 18 in the members 11 and 12 jointly constitute a longitudinally extending bore or opening 25 95 (see Figure 3).

In order to connect the plug to the wires 26 of the electric cord it is merely necessary to wrap the bared ends of the wires about 105 the shorter branches of the connector blades whereby when the latter are seated in their grooves 20-21 and the members 11 and 12 are bolted together to securely position the connector blades therebetween the conductor 110

wires will be maintained in good electrical contact with the blades. It will of course be evident that when the members 11 and 12 have been so clamped together with the connector blades 24 in position and in electrical contact with the wires 26 the terminal ends of the latter will have been entirely enclosed within the passageways 27 formed by the registering grooves 14 of the members 11 and 12.

The openings 13 in the body members 11 and 12 are arranged to register when the latter have been clamped together so as to provide a central opening extending transversely through the body of the completely assembled plug, and through which opening one may insert his finger to more readily and conveniently remove or withdraw the plug from its socket. By providing this means for withdrawing the plug the temptation and the necessity to remove it by pulling on the electric cord is practically eliminated with the result that the wear and tear on the cord is considerably reduced.

In Figure 5 is shown a modified form of the invention embodying the features pointed out above in connection with construction shown in Figures 1 to 4. In this modified form of attachment plug it will be seen that instead of providing two main body members which are counterpart of one another, there is provided an integrally formed annular portion 28 having passageways 14' in opposite sides thereof, the outer ends of which passageways terminate in a common longitudinally extending bore or opening 25'. The formation of this annular portion of the plug body obviates the necessity for the bolt or screw 23 shown in Figures 1 to 4. The contact end of the body portion 28 is provided with a lateral head 29 similar in all respects to the head formed on the body portion 11 of the construction shown in Figure 3, and the inner face thereof, which lies in a plane corresponding to the median plane of the annular body 28, is provided with grooves 30 in extension of the passageways 14'. A complementally formed head portion 31 is arranged to be clamped in the position shown in Figure 5 by means of the screw or bolt 22. The face of this separable head portion 31 which abuts the face of the head portion 29 of the body 28 is also provided with grooves in extension of the passageways 14' such that when the members 28 and 31 are clamped together the grooves 30 together form continuations of the passageways 14' leading to the inner ends of the contact blades 24. These contact blades are similar in all respects to the blades shown in Figures 1 to 3 and are arranged to be clamped in position with the ends of the wires 26 secured thereto in substantially the manner hereinbefore described.

It is to be understood that in the foregoing

description and in the appended claims, the term "annular" relating to the central opening in the plug body is intended to define any form of such opening regardless whether it be of circular, oval or other configuration.

While the foregoing describes the present preferred form of the invention it is of course to be understood that various changes and modifications thereof may be made from time to time without departing from the real spirit or principles of the invention and it is accordingly intended to claim the same broadly as well as specifically as indicated in the following appended claims.

What is claimed as new and useful is:

1. An attachment plug comprising a pair of complementally formed main body members, said members being each provided with laterally spaced grooves and an enlarged finger receiving opening between said grooves, and means for securing said body members together with said grooves and opening of one of said members in registry with the corresponding grooves and opening of the other of said members.

2. An attachment plug comprising a pair of main body members arranged to be secured together in assembled relation, a pair of contact blades clamped between said members against lateral or longitudinal displacement with respect thereto, said plug being provided with a central finger receiving opening extending transversely through the body thereof.

3. An attachment plug comprising a pair of complementally formed main body members, each of said body members being of substantially annular form and provided at one end thereof with a lateral projecting head of substantially semi-circular form, a pair of contact blades arranged to be clamped in position between the heads of said body members, and means for securely clamping said members together with the annular portions thereof in registry with one another whereby to provide a transversely extending opening through the body of the assembled plug adapted to receive the finger of a hand for removing the plug from its socket.

4. An attachment plug comprising a main body portion of substantially annular form, a head at one end of said annular body lying in a plane substantially at right angles to the plane of said annular body, and a pair of contact blades projecting outwardly from said head, said annular body portion being provided with conductor receiving grooves in opposite sides thereof leading to the inner ends of said contact blades.

Signed at Philadelphia, county of Philadelphia, State of Pennsylvania, this 20th day of May, 1927.

GEORGE LIPSCHUTZ.
